UNITED STATES PATENT OFFICE.

WAS KAMADA, OF NEW YORK, N. Y.

DETACHABLE SHOE HEEL.

Application filed February 16, 1928. Serial No. 254,767.

The invention relates to detachable heels for shoes, and has for its object to provide a device of this character whereby when the heel becomes worn it can be easily and quickly removed and replaced with a new one, or if desired placed on the other shoe where the worn portion will be on the inside of the shoe, consequently concealed from view to a great extent.

10 A further object is to provide the detachable heel with spring male members adjacent its marginal edge and which spring male members are forced through eyes carried by the permanent portion of the shoe to positions above the eyes where they will expand into close engagement with the upper edges of the eye for rigidly holding the detachable heel in place and taking up any slack incident to wear by their expansive force, thereby preventing lateral movement of the detachable heel during a walking operation.

A further object is to provide a leather layer in which the eyes are placed in accurate positions, and which layer may be secured 25 to the heel of the shoe with its eyes in registration with apertures in the fixed heel portion of the shoe, for the reception of the expansive male members carried by the detachable heel.

30 A further object is to provide the male members with elongated shanks terminating in annular members imbedded in the detachable heel, and with annular members adjacent their outer ends and imbedded in the inner face of the detachable heel, thereby rigidly bracing the male members and anchoring the same.

With the above and other objects in view the invention resides in the combination and arrangement of parts as hereinafter set forth, shown in the drawing, described and claimed, it being understood that changes in the precise embodiment of the invention may be made within the scope of what is claimed 45 without departing from the spirit of the invention.

In the drawing:

Figure 1 is a bottom perspective view of the heel portion of a shoe showing the detachable heel removed.

Figure 2 is a perspective view of the detachable heel.

Figure 3 is a vertical longitudinal sectional view through the heel of the shoe and the detachable heel.

Figure 4 is an enlarged vertical transverse sectional view through the fastening means and adjacent portions of the heel.

Referring to the drawing the numeral 1 designates the upper of a conventional form of shoe and 2 the permanent portion of the heel. Secured to the under side of the permanent portion 2 of the heel, preferably by cement 3 is a layer of leather 4, which layer of leather at spaced points around its marginal edge is 65 provided with a plurality of metallic eyes 5 having their opposite sides imbedded in the layer of leather 4 whereby adjacent engaging parts will closely engage the layer of leather 4. The eyes 5 are rigid and are adapted to receive therethrough the expansive male member heads 6, which heads contract as they are forced through the eyes 5 and expand into close binding engagement with the annular edges 7 of the eyes after the heads are in position as shown in Figure 4, and in the apertures 8 of the heel portion 2, and by which expansive action any play which may develop is taken up, and consequently lateral movement of the detachable heel 9 is prevented during a 70 walking operation, which would not be the case if an expansive male member 6 were not used.

The male members 6 are provided with elongated shanks 10, which shanks extend downwardly into the detachable heel 9 and are provided with integral discs 11 and 12. The discs 12 as well as the shank 10 are imbedded in the heel 9, which is preferably formed from rubber, while the discs 11 are imbedded in the upper surface of the heel 9 into positions where they will engage the lower sides of the eyes 5, consequently will prevent the eyes from wearing holes in the upper side of the detachable heel 9, which in time, incident to walking 95 would cause the male members to project too far upwardly and allow development of play, which would move the male members out of engagement with the eyes at 7, consequently allowing lateral movement of the detachable heel during a walking operation.

From the above it will be seen that a detachable heel is provided wherein expansible fasteners are used which will prevent lateral

movement of the heel during a walking operation and a heel provided which may be easily and quickly removed and replaced with a new heel as the heel wears, or if desired a 5 worn heel may be shifted to the opposite shoe, which is particularly desirable where the heel is worn on one side.

The invention having been set forth what is claimed as new and useful is:

- 10 1. A detachable heel comprising a fixed portion, a layer of material attached to said fixed portion, a plurality of eyes extending around said layer of material adjacent its marginal edge in spaced relation, annular flanges carried by said eyes and imbedded in opposite sides of the layer of material, apertures in the fixed portion of the heel in registration with the eyes, a detachable heel portion, and a plurality of spaced expansible male members carried by the detachable portion of the heel and 15 extending through the eyes and having ex-
- 20

pansive engagement with the upper inner edges of the eyes.

2. A detachable heel comprising a fixed portion, a layer of material carried by said fixed portion, a plurality of eyes carried by said layer of material, a plurality of expansive male members carried by a detachable heel and extending through the eyes into chambers in the fixed portion of the heel, said expansive 25 members having expansive engagement with the inner edges of the eyes, shanks carried by the expansive male members, spaced discs carried by said shanks, said shanks and one of their discs being entirely imbedded in the detachable heel, the other disc of the shank being imbedded in the upper side of the heel and engaging the eyes. 30

In testimony whereof I hereunto affix my signature.
